US00D625415S

(12) **United States Design Patent**
Otto et al.

(10) **Patent No.:** **US D625,415 S**
(45) **Date of Patent:** **** Oct. 12, 2010**

(54) **FEMORAL IMPLANT**

(75) Inventors: **Jason Otto**, Plantation, FL (US); **Amit Mistry**, Plantation, FL (US); **Martin Roche**, Fort Lauderdale, FL (US); **Thomas Coon**, Redding, CA (US); **Scott A. Banks**, Gainesville, FL (US); **Dana C. Mears**, Pittsburgh, PA (US); **Alastair J. Clemow**, Princeton, NJ (US)

(73) Assignees: **Mako Surgical Corp.**, Ft. Lauderdale, FL (US); **University of Florida Research Foundation, Inc.**, Gainesville, FL (US)

(**) Term: **14 Years**

(21) Appl. No.: **29/338,104**

(22) Filed: **Jun. 4, 2009**

Related U.S. Application Data

(63) Continuation of application No. 29/329,712, filed on Dec. 19, 2008, now abandoned, and a continuation of application No. 29/329,715, filed on Dec. 19, 2008, now abandoned.

CLAIM

The ornamental design for a femoral implant, as shown and described.

DESCRIPTION

FIG. 1 is a top plan view of a femoral implant showing our new design;

FIG. 2 is a bottom plan view of the femoral implant;

FIG. 3 is a front elevational view of the femoral implant;

FIG. 4 is a back elevational view of the femoral implant;

FIG. 5 is a side elevational view of the femoral implant;

FIG. 6 is an opposite side elevational view of the femoral implant; and,

FIG. 7 is a perspective view of the femoral implant.

The broken lines shown in the drawings illustrate structural environment and form no part of the claimed design.
